TOY WIND ORGAN

Lewis Davis, London, England, assignor to Selcol Products Limited, London, England, a company of Great Britain

Filed Feb. 4, 1960, Ser. No. 59,263

Claims priority, application Great Britain Jan. 5, 1960

Term of patent 7 years

(Cl. D56—1)

Figure 1 is a top perspective view of a toy wind organ, showing my new design;

Figure 2 is a bottom perspective view; and
Figure 3 is a side elevational view thereof.

I claim:

The ornamental design for a toy wind organ, substantially as shown.
